UNITED STATES PATENT OFFICE

104,839

DESIGN FOR A CHIFFOROBE

Abraham G. Feldman, Chicago, Ill.

Application April 29, 1937, Serial No. 69,056

Term of patent 3½ years

To all whom it may concern:

Be it known that I, Abraham G. Feldman, a citizen of the United States, residing at Chicago, in the county of Cook and State of Illinois, have invented a new, original, and ornamental Design for Chifforobes, of which the following is a specification, reference being had to the accompanying drawing, forming part thereof.

The figure is a perspective view of a chifforobe, showing my new design.

I claim:

The ornamental design for a chifforobe, as shown.

ABRAHAM G. FELDMAN.
